UNITED STATES PATENT OFFICE

JOSEPH SACHS, OF WEST HARTFORD, CONNECTICUT

ELECTRIC-CIRCUIT-CONTROLLING APPLIANCE

Application filed March 10, 1927, Serial No. 174,350. Renewed December 7, 1929.

The invention relates to a circuit controlling appliance, such as a fused switch and it is especially applicable to a fused switch having the fuse contacts thereof at the front 5 and having the switching device located at least in part in the space between a transverse plane through the fuse contacts and a rear supporting wall. The switching device preferably includes a sliding member movable 10 parallelly with the rear supporting wall. A construction embodying the present invention is similar in many respects to those disclosed in my copending applications for electric circuit controlling appliance, Serial No. 153,966 filed Dec. 10th, 1926 and for electric circuit controlling appliance, Serial No. 165,645, filed Feb. 3, 1927.

In the first said copending application I have disclosed a fused switch having a base 20 with fuse contacts carried thereby at the front and with stationary switch contacts also carried thereby and located behind the plane of a rearward facing surface of the base. The fuse contacts and the switch contacts are thus held in fixed relationship with the base and with each other. For establishing an electrical connection between the switch contacts there is provided a rectilinearly movable switching member which is located at least in part behind the base.

In the second aforesaid copending application I have disclosed a fused switch also having a base with fused contacts carried thereby at the front, and said fused switch 35 also has stationary switch contacts located behind the plane of a rearward facing surface of the base, but the said stationary switch contacts, instead of being permanently connected with the base, are connected with and mounted upon a rear support. The base with its fuse contacts is detachably mounted in fixed relation with the base and the rectilinearly movable switching member of the 40 switching device is located at least in part behind the base. When the base with the fuse contacts thereon is removed the switching device is easily accessible, all of the parts thereof remaining in their normal operative 45 relationship. With the base removed as de-

scribed the switching member can be easily removed in the forward direction.

In accordance with the present invention the fuse contacts and the switch contacts are mounted in fixed relationship with each other, but instead of mounting all of the said contacts upon a base as in the first construction, and instead of mounting the fuse contacts on the base and the switch contacts on the rear support as in the second said construction, I mount all of the contacts upon the rear support independently of any base or equivalent member. The relationship is such that the switching device is located at least in part behind a transverse plane 55 through the rear parts of the fuse contacts, but nevertheless the fuse contacts and the switch contacts are so positioned that access can be conveniently had to the switch contacts without disturbing the fuse contacts. Preferably the sliding switching member is 60 removable in the forward direction without disturbing the fuse contacts.

A fused switch embodying the invention may be and preferably is enclosed within a cabinet. When so enclosed, it may be desirable to provide means whereby access may be had to the fuse contacts without however permitting access to the switch. In accordance with the present invention such a means 75 is provided, this taking the form of a removable insulating guard which permits access to the switching device as aforesaid.

The cabinet enclosing the fused switch may, if desired, be adapted to be readily associated with a meter, so as to protect the latter; and if desired, meter testing means may be provided in the cabinet in association with the fused switch. The cabinet, whether or not associated with a meter, may be provided with a cover normally covering the fuses and co-operatively related or interlocked with the switching device, so that the cover cannot be moved to open position when the switch is closed and so that the switch 90 cannot be closed when the cover is open.

The general object of the invention is to provide a fused switch having the characteristics described. Further and more specific objects are to provide certain novel and 100

advantageous details of construction such as will now be described.

In the accompanying drawings, I have shown several embodiments of the invention, but it will be understood that the drawings are intended for illustrative purposes only and are not to be construed as limiting or defining the scope of the invention, the claims forming a part of this specification being relied upon for that purpose.

10 Of the drawings:

Figure 1 is a front view of an appliance embodying the invention, parts of the enclosing cabinet being broken away to show the interior construction.

15 Fig. 2 is a bottom view of the parts shown in Fig. 1, the enclosing cabinet being shown in section.

20 Fig. 3 is a vertical sectional view taken along the line 3—3 of Fig. 1.

25 Fig. 4 is a fragmentary view similar to Fig. 2 but showing the position assumed by the movable switching member while being removed.

30 Fig. 5 is a view similar to Fig. 1, but showing in dot-and-dash lines the position of a removable guard adapted to be associated with the fuse and switch parts.

35 Fig. 6 is a bottom view of the parts shown in Fig. 5, the enclosing cabinet being shown in section.

Fig. 7 is a vertical sectional view taken along the line 7—7 of Fig. 5.

40 Fig. 8 is a detail perspective view of the removable guard shown in Figs. 5 to 7.

45 Fig. 9 is a view similar to Figs. 1 and 5, but showing a different embodiment of the invention which includes meter testing devices.

50 Fig. 10 is a bottom view of the parts shown in Fig. 9, this view being partly in section.

Fig. 11 is a vertical sectional view taken along the line 11—11 of Fig. 9.

55 Fig. 12 is a vertical sectional view taken along the line 12—12 of Fig. 9.

Fig. 13 is a view similar to Figs. 1, 5 and 9 but showing still another embodiment of the invention.

60 Fig. 14 is a bottom view of the parts shown in Fig. 13, the enclosing cabinet being shown in section.

Fig. 15 is a vertical view taken along the line 15—15 of Fig. 13.

65 In each of the several embodiments of the invention shown in the drawings, there are two pairs of fuse contacts and two separate switching devices but it will be understood that the invention is not necessarily limited to any particular number of fuses and switches. The fuse and switch parts are shown symmetrically disposed with respect to the vertical central plane of the appliance, and for the sake of convenience and simplicity of description, I will in the main confine 70 the description to those parts on one side of

the said plane, it being understood that the parts on the other side are, or may be, the same in construction except for reversal of positions.

75 The fused switch construction shown in Figs. 1 to 4 will be first described. Fuse receiving contacts 1 and 2 are provided, and means are provided for supporting these contacts in fixed spaced relationship to a rear support. When there is an enclosing cabinet this rear support may be the rear wall of the cabinet. The fuse contacts as shown are adapted for receiving a cartridge enclosed fuse such as F, but it will be understood that the invention is not limited for use with fuses 80 of this particular type.

85 In addition to the main rear support, I prefer to also provide an independent insulating supporting device which is ordinarily secured to the main rear support but which is nevertheless separate therefrom. This supporting device may comprise a single block, bar or plate of insulating material or two or more such bars or plates. As shown the supporting device comprises two insulating bars 3, 3. When such a separate supporting device is provided, the fuse contacts are also normally held in fixed spaced relationship therewith.

90 Preferably, a plurality of forward projecting supporting elements are provided which are respectively connected at their forward portions with the fuse contacts 1 and 2 and are connected at their rear portions with the main rear support, preferably indirectly by means of the separate supporting device 3. The elements therefore serve to support the fuse contacts 1 and 2 in the described relationship with the said rear support. As shown, there are two such supporting elements represented at 4 and 5, these having their front portions connected directly with the fuse contacts 1 and 2 by means of screws 6 and 7 and having their rear portions connected with the supporting device 3 by means of screws 8, 8. The fuse contacts are thus electrically connected with the supporting elements. The supporting elements 4 and 5 are shown as being Z-shaped but as to this there may be wide variation.

95 Located at least in part in the space behind a transverse vertical plane extending through the rear parts of the fuse contacts 1 and 2 is a switching device. In referring to a transverse vertical plane I mean one parallel or substantially parallel with the main rear support for the appliance. Preferably the switching device comprises two or more normally stationary switch contacts and a switching element which is rectilinearly movable substantially parallelly with the aforesaid transverse plane and with the front face of the support.

100 As concerns some of the broader phases of the invention, the location and mounting of

the stationary switch contacts can be varied, but, preferably and in accordance with other phases of the invention, at least one of the said switch contacts is mounted directly upon and electrically connected with one of the supporting elements 4 or 5. Preferably and as shown, two switch contacts 9 and 10 are mounted upon and electrically connected with the two supporting elements 4 and 5 respectively, which elements are electrically connected respectively with the fuse contacts 1 and 2 as already described. The contacts are preferably of a resilient U-shaped form as shown. By means of these switch contacts 9 and 10 the circuit may be broken at both sides of the fuse as will presently appear.

Each of the said switch contacts 9 and 10 is one of a pair. The other contacts of the pairs are shown at 11 and 12 respectively and they are similar respectively to the contacts 9 and 10 but positioned in opposed relationship thereto. Contact supporting elements 13 and 14 are provided for the contacts 11 and 12, these preferably being similar to the main supporting elements 4 and 5 and being similarly secured to the supporting device 3 as by screws 15 and 16. The contact supporting elements 13 and 14 also carry, respectively, wire connecting terminals 17 and 18 each adapted for the connection of either an incoming circuit wire or an outgoing circuit wire. I have shown terminals of the solder lug type, but I do not so limit myself.

For establishing or breaking electrical connection between the switch contacts of the said pairs 9, 11 and 10, 12 I provide for each pair a switching element which is rectilinearly movable substantially parallelly with the front face of the supporting device and with the rear face of the fuse base. When there are two parts of stationary switch contacts there are two conducting switching elements 19 and 20 insulated from each other and adapted respectively to engage and disengage the said normally stationary switch contacts. The two conducting switching elements 19 and 20 are preferably carried by an insulating element 21, which with the said conducting elements constitutes a rectilinearly movable switching member. The insulating element 21 is preferably in the form of a flat plate, the said conducting elements 19 and 20 extending through it and projecting somewhat beyond the opposed surfaces thereof as shown. The details of the switching member may be as shown in my said copending application for electric circuit controlling appliance, Ser. No. 153,966 filed Dec. 10, 1926.

When the stationary switch contacts are located as shown, the said flat insulating element 21 is arranged perpendicularly to the supporting device and to the fuse base. The said element preferably engages at its inner edge with the insulating bars 3, 3 of the sup-

porting device so as to be guided in part thereby.

From the foregoing description, it will be apparent that when the switching member is in the "on" position, as shown in Fig. 1, a circuit will be established from the wire connecting terminal 17 through the contact supporting element 13 and the switch contacts 11, 19 and 9, to the supporting element 4 and thence to the fuse contact 1. Similarly a connection is established from the fuse contact 2 through the supporting element 5 and the switch contacts 10, 20 and 12 to the contact supporting element 14 and the wire connecting terminal 18. When the switching member is moved upward from the position shown in Fig. 1, the elements 19 and 20 will be disengaged from the stationary switch contacts and circuit will be broken at two points at each side of the fuse, thus making a total of four breaks. The insulating element 21 of the switching member serves not only as a carrier for the contacts 19 and 20, but it also serves as a barrier which is moved between the opposite stationary contacts immediately upon the disengagement at the corresponding movable contact 19 or 20 therefrom. The switching member is entirely free to adjust itself laterally to conform to the positions of the several stationary switch contacts. If there are any defects in the initial construction or mounting of these stationary contacts or in the subsequent adjustment thereof, the switching member will conform thereto and will at all times effect firm engagement with the contact and will establish effective electrical connections therewith.

So far as the present invention is concerned, I do not narrowly limit myself in regard to the exact location of the stationary switch contacts. I have shown the two pairs of stationary contacts offset upward and downward respectively away from the fuse contacts so as to be clearly visible and easily accessible without in any way disturbing the said fuse contacts.

From the foregoing description, it will be apparent that I have provided a fused switch construction having an entirely novel and highly advantageous combinational relationship between the fuse and switch parts. The fuse and switch parts are all carried by the rear support without any insulating fuse carrying base at the front. The fuse contacts are at the front of the device and are therefore easily accessible, and the switch parts are located in the region behind a transverse plane through the fuse contacts, thus greatly economizing space.

Although the switching device is behind a transverse plane through the rear parts of the fuse contacts, it is nevertheless so located laterally as to bring the movable switching member 21 sufficiently far to one side of the fuse contacts to permit its withdrawal or re-

moval in the forward direction without interfering with the said fuse contacts or with the fuse therein. In addition, as already stated, the stationary contacts of the switching device are preferably so located as to be clearly visible and easily accessible without in any way disturbing the fuse contacts or the fuse therein. When there are two pairs of fuse contacts and two separate switching devices as shown, the fuse contacts of the two pairs are preferably arranged side by side at the center and relatively closely spaced. The switching devices are preferably arranged more or less at the rear of the fuse contacts as shown and described, and, whether arranged at the rear or not, they are preferably so positioned that the movable switching members are at the outer sides of the respective pairs of fuse contacts. This makes it possible for the said movable members to be removed in the forward direction as described without interfering with the said fuse contacts and without interfering with the desired close spacing therebetween.

Preferably, the fused switch unit described is enclosed in a casing or cabinet, this ordinarily being so constructed that it can be sealed to prevent unauthorized access to any of the parts, excepting in some cases the fuse contacts. In Figs. 1 to 4, I have shown an enclosing cabinet 22 of sheet metal having a rear wall 23, side walls 24, 24 and end walls 25, 25. The cabinet has an openable front cover 26, which is shown as being hinged at 27 to the bottom end wall 25. Suitable means such as a spring latch 28 is provided for holding the cover in closed position and a seal 29 may be provided for preventing the opening of the cover except by breaking the seal. The fused switch unit as a whole is secured to the rear wall 23 of the cabinet by means of screws 30, 30 engaging the bars 3, 3 of the supporting device. If desired, a plate 31 of insulating material may be interposed between the supporting device and the rear wall of the cabinet.

A means is provided for operating the switching member or members and when there is an enclosing cabinet, such as 22, the said means includes a handle located externally of the cabinet so that the switch can be operated when the cabinet is closed. The cabinet may be utilized as a means for supporting the switch operating means and as shown, there is an operating spindle comprising a rod 32 including two pivot sections 33 and 34 extending through bearing openings in the side walls 24, 24 of the cabinet. The said rod is bent to form a manually operable handle 35 outside of the cabinet and also to form a crank section 36 inside of the cabinet and between the pivot sections.

The crank section is operatively connected with the movable switch member so as to permit the assembly or disassembly of the mov-

able switching member with or from the operating means and the cabinet by the simple act of moving it rearward or forward. For this purpose, I have shown in each insulating element 21 a slot 37 adapted to receive the crank section 36. The slot 37 is preferably open at one end, that is, at the back end, so as to facilitate assembly or disassembly as described. The slot 37 is shown as being near the middle of the insulating element, this location being ordinarily preferable.

From the foregoing description, it will be obvious that by moving the handle 35 each of the switch members can be moved longitudinally upward or downward, as desired. With the handle 35 in its uppermost position as shown in Figs. 1 and 3, the switching members will be held in their lowermost positions, thus completing the circuit through the appliance as already described. When the handle 35 is moved to its lower position, the switching members will be moved to their upper positions, thus separating the movable contacts 19 and 20 from the stationary contacts 9, 11 and 10, 12 respectively and thus breaking each leg of the circuit at four points as already described.

Preferably the supporting elements 4 and 5 of each pair supporting the corresponding fuse contacts 1 and 2 are connected together by means of a member or plate 38 of insulating material which is shown as being held in place by the same screws 6 and 7 which connect the fuse contacts with the supporting elements. This plate 38 serves to hold the two supporting elements in their proper relative positions, and preferably has further functions as will presently appear. It will be observed that the plate 38 is relatively small and that the switch contacts are out of direct rearward register with the plate so as not to be in any way obstructed thereby. When two plates 38, 38 are provided as described for two pairs of fuse contacts the said fuse contacts and the stationary switch parts are all held in fixed relation with each other and with the insulating bars 3, 3. All of these parts constitute a unit which can, if desired, be assembled with or removed from the rear support and operating spindle without disturbing their assembled relationship.

As already fully described, I have provided a switching device having a rectilinearly movable main switching member, and in accordance with one phase of the invention I have provided a holding means for the switching member which is so related thereto that the switching member can be released for removal in the forward direction by effecting relative lateral movement between the holding means and the said member. As illustrated, the switching member is laterally movable and the holding means is stationary, but as to this, there may be variation. As concerns this feature of the invention, I do not neces-

sarily limit myself to a switch which is combined with fuse contacts.

When a connecting plate 38 is provided between the supporting elements for the stationary switch contacts, I preferably utilize this plate as the means for normally holding the rectilinearly movable switching member against forward movement. Normally, as clearly shown in Fig. 2, the switching member is adapted to engage at its rear edge with the bars 3, 3 and at its front edge with the plate 38, the switching member being thus guided for rectilinear movement.

In order that the switching member may be removed from the supporting device and from the stationary switch contacts, the arrangement is such that the switching member can be released from the holding means, that is, from the plate 38, by being moved laterally as shown in Fig. 4. The several stationary switch contacts are sufficiently resilient to permit the lateral movement or tilting of the switching member, as shown. The plate 38 preferably overlaps the normal position of the switch member only to a slight extent, thus avoiding any necessity for excessive lateral movement or tilting. When the movable switch member has been moved laterally as shown in Fig. 4, it can then be withdrawn in a forward direction so as to entirely disengage the stationary switch contacts. It will be understood that the switching member is ordinarily moved to its "off" position before being withdrawn. The slot 37 permits withdrawal of the member from the operating spindle.

In Figs. 5 to 8, I have shown a construction which is in the main similar to that shown in Figs. 1 to 4. The details of the fuse contacts and switch parts and of the mountings therefor are, or may be, exactly the same as already described and repetition of description will be unnecessary.

The construction differs essentially in that provision is made whereby access may be had to the fuse contacts without permitting access to the switch or other parts within the cabinet. Accordingly, the cover 26^a of the cabinet is provided with an opening 39 through which the said fuses and contacts are accessible. In order to prevent access through the said opening in the cover to the switches and other parts, a suitable guard is provided, this guard being removable in order to permit free access to the switch parts when the cover is open and in order to permit the removal of the movable switch members, as already described. This guard is shown at 40 and it is illustrated as being removably connected with the supporting elements 4 and 5 which support the fuse contacts, though I do not limit myself to this manner of mounting. Spring clips 41, 41 are provided for resiliently holding the guard

in place, these clips however permitting the guard to be easily removed manually.

The guard 40 is so formed and normally so located that it surrounds the fuses and serves to entirely close the said opening 39 in the cover when the cover is in closed position. The cover when closed cooperates with the clips 41, 41 in holding the guard 40 in position. At its inner end, the guard cooperates with the plates 38, 38 to prevent access to the interior of the cabinet. The guard preferably includes a central wall or baffle 42 positioned between the fuses.

The cover 26^a preferably has an auxiliary cover mounted thereon, which cover may be interlocked with the switch to prevent its movement to open position when the switch is closed. I have shown, however, a cover 43 which is not so interlocked, this cover being pivoted to the main cover at 44 and being provided with a spring 45 which tends to hold it in closed position.

It will be apparent that when the main cover is closed, access can be had to the fuses by opening the auxiliary cover. The guard 40 serves, however, to prevent access being had to the switches or to any other parts within the cabinet when the auxiliary cover is open. However, when the main cover 26^a is opened, the guard 40 can be easily removed, thus exposing the switch parts and permitting the movable switching members 21, 21 to be easily removed as already described.

In Figs. 9 to 12, I have shown an embodiment of the invention which is similar to those shown in Figs. 1 to 4 and in Figs. 5 to 8, but which also includes certain additional features. The construction as concerns the fuse contacts and the switching devices is substantially the same as that already described and repetition of description is unnecessary.

Instead of providing two separate plates 38, 38 as shown in Figs. 1 and 5, I have shown a single plate 38^b which cooperates with the fuse contacts of both pairs and obstructs the space between them. The plate 38^b is shown as being somewhat differently mounted. Instead of being held directly by the screws which hold the fuse contacts, the plate 38^b is provided with relatively large rectangular openings into which the outer end portions of the supporting elements 4^b and 5^b extend. Each of the said elements is provided with an inward offset lip 46 as shown in Fig. 11, the several lips being adapted to engage the inner surface of the plate and thus hold the plate against rearward movement. The plate is held against forward movement by means of the fuse contacts themselves as clearly shown in Fig. 10.

A guard 40^b is provided similar in function to the guard 40 already described in connection with Figs. 5 to 8. However, inasmuch as the plate 38^b extends across from one pair of

5 fuse contacts to the other pair of fuse contacts, it is not necessary to provide the guard with a central wall such as the wall 42. The guard 40^b is similar to the guard 40 in that it is removable and in that it is held in place by the cabinet cover when the cover is closed. However, instead of being held in place primarily by spring clips or other means connected with the supporting elements, the 10 guard 40^b is connected directly with the cover 26^b so as to be automatically removed whenever the cover is opened.

15 The cover 26^b is provided with an opening 39^b which communicates with the interior of the guard 40^b. The guard surrounds the opening and serves when the cover 26^b is closed to prevent access through the opening with any conducting parts in the cabinet other than the fuse contacts and fuses. As 20 shown, the cover 26^b is flat and there is provided an auxiliary cover for the opening 39^b and the parts are so constructed that the fuse cover cannot be opened when the switch handle 35^b is in the position corresponding to the 25 closed position of the switch and so that the handle 35^b cannot be moved to the position corresponding to the closed position of the switch when the cover is open. I have shown a sidewise opening flat cover 43^b for the fuses, 30 this cover preferably directly engaging the main cover 26^b for sliding movement thereon. Rigidly secured to the main cover 26^b is a sheet metal guide 47 having an opening 48^b therein which registers with the opening 39^b 35 in the main cover. The guide 47 is spaced from the main cover so that the fuse cover 43^b is slidably mounted between the said parts. The said fuse cover 43^b is provided with a knob 49 which serves as a means for 40 moving the fuse cover and which also serves as a stop for limiting the movement of the said cover in either direction. Fig. 10 shows the cover 43^b in its left hand closed position. It will be observed that when the 45 fuse cover is in closed position and the switch handle 35^b in the switch closing position, the said handle directly obstructs the cover and prevents the opening movement thereof. When the fuse cover is in its open position 50 having been moved to the right from the position shown in Fig. 10, the said cover directly obstructs the handle 35^b and prevents its movement to switch closing position. The 55 specific construction and the interrelationship as herein described between a sidewise opening cover and a switch operating handle are not claimed as part of the present invention, these being set forth in my patents for 60 enclosed fused switches, Nos. 1,721,493, 1,721,494 and 1,721,495 all issued July 16, 1929.

65 The construction shown in Figs. 9 to 12 also differs in that provision is made for the protective association of the enclosed appliance

with an electric meter and that provision is also made for the testing of the meter.

As shown in Fig. 10, the cabinet 22^b has its upper end wall 25^b provided with an opening therein adapted to receive and approximately fit the terminal portion of an electric meter M. With this construction, the cabinet 22^b serves not only to enclose the fused switch, but also to enclose the terminal portion of the meter together with the connections between the meter and the said fused switch. 75

In addition to the parts already described, I have also provided means for facilitating the testing of the meter. The details of the testing means may be varied according to the conditions of use. For three wire service I preferably provide testing means for each of two legs of the circuit, each means comprising at least one movable test link adapted to be included in the circuit between the meter and the load wires and adapted to be so moved as to disconnect the meter from the load wires while testing is being carried on. The testing means may be variously mounted but I have shown two insulating members 50 for supporting them, these members being at the sides of the fuse contacts. While I do not necessarily limit myself to the location of the testing means directly at the sides of the fuse contacts, it is nevertheless important to locate them otherwise than directly behind the fuse contacts. They should be out of rearward register with the fuse contacts in order to insure visibility and accessibility and they should preferably be located otherwise than in front of the switching device in order not to interfere with the latter. 95

Ordinarily and preferably, the incoming circuit wires S, S are connected with the terminals 17^b, 17^b and as shown a neutral wire S' is also provided. The circuit extends from these terminals 17^b, 17^b, through the switch and fuse parts in the manner already described to the terminals 18^b, 18^b, these latter terminals being connected with the supporting elements 5^b, 5^b in a manner to be described in detail. The said terminals 18^b, 18^b are indirectly connected with the outgoing or load circuit wires through the meter M, connections C¹ and C² extending from the said terminals 18^b, 18^b to the meter. Other meter connections C³ and C⁴ extend from the meter M to wire connecting terminals 51, 51 mounted on the blocks 50, 50 preferably near the outer edges thereof. The outgoing circuit wires L, L are connected directly with terminals 52, 52 which terminals are connected respectively with the terminals 51, 51 by means of movable testing links 53, 53. The testing links 53, 53 are of a well known construction, each link being slotted near its ends and thus adapted to receive studs 54 and 55 connected respectively with the terminals 51 and 52. It will be seen that by removing 120 125 130 135 140 145 150 155 160 165 170 175 180 185 190 195 200 205 210 215 220 225 230 235 240 245 250 255 260 265 270 275 280 285 290 295 300 305 310 315 320 325 the links 53, 53, the circuit may be broken between the said terminals 51, 51 and 52, 52.

The blocks 50 are supported upon the main supporting device, in this case the insulating bars 3^b, 3^b, in part by extensions 56 on the supporting elements 5^b, 5^b and in part by supplemental supporting elements 57, 57.

Preferably, in addition to the testing links 53, 53 I provide other similar links 58, 58 interposed between the terminals 18^b, 18^b, and the corresponding switch contact supporting elements 5^b, 5^b. As already stated each element 5^b is provided with an extension 56. At the front of each block is a short conductor 59 connected with the corresponding extension 56 by means of screws 60 and 61. The said testing link 58 is connected with the screw 61 and with a similar screw 62 connected with the terminal 18^b.

20 In addition to the removable links 53 and 58, I also provide contacts adapted for the attachment of a short circuiting connection from each switch contact supporting element 5^b to the corresponding terminal 52. For 25 this purpose I utilize the before-mentioned stud 60 and a similar stud 63 connected with the corresponding terminal 52. A link 64 may be provided as shown in dot-and-dash lines in Figs. 9 and 10 for connecting the 30 said studs 60 and 63. It will be seen that when the two links 64, 64 are in place, the circuit will extend directly through the switch and fuse to the terminals 52, 52. It is then possible to either partly or entirely 35 disconnect the meter by removing some or all of the links 53 and 58.

The specific combination of meter testing devices with a circuit controlling appliance such as herein shown and described does not 40 of itself constitute a part of the present invention, being set forth and claimed in my copending application for electric meter service appliance Serial No. 247,730 filed January 18, 1928.

45 From the foregoing description, it will be observed that I have provided a complete meter service appliance including fuses, switches and meter testing means and that the several parts of this appliance are so 50 constructed and related that the switch parts are easily visible and conveniently accessible without disturbing any of the other parts and without breaking any electrical connections. If desired, the movable members of 55 the switches can be entirely removed without disturbing any conducting parts other than the said members themselves. It will further be observed that the arrangement is such that the removable guard 40 while permitting access to the fuse parts nevertheless prevents access either to the switch parts or the testing means, thus preventing unauthorized manipulation of these latter parts.

In Figs. 13 to 15, I have shown a still different construction which includes certain

features already described and also certain other features. The construction and mounting of the switch and fuse parts are, or may be, the same as already described, particularly in connection with Figs. 9 to 12. The upper stationary switch contacts are shown as reversed in position, but this is not essential. I have shown a guard 40^c surrounding the fuses which may be similar to the guard 40 shown in Figs. 5 to 8. The guard has a central wall 42^c and screws 65, 65 extend through this wall and connect the guard 42^c with the plate 38^c. The cabinet 22^c is, or may be, substantially the same as that shown in Figs. 9 to 12, the principal difference being that the guard 40^c is not attached to the cover.

The supporting device for the several parts is in the form of a single block 3^c of insulating material instead of being in the form of two separate blocks as shown in the other figures. It is secured in place by means of screws 30^c, 30^c.

Testing means are provided which are similar in function to those shown in Figs. 9 to 12, but which are differently located. Instead of being carried by separate blocks such as 50, 50, they are carried directly upon the rear supporting device or block 3^c.

Each supporting element 14^c for the corresponding switch contact 12^c is provided with an extension 66 which is at the front of the block 3^c and which corresponds in function to the conductor 59 shown in Figs. 9 and 12. This extension is held in place by means of screws 60^c and 61^c. A conductor 67 is provided which is connected with the terminal 18^c and which is held in place in part by a screw 62^c. A test link 58^c which is, or may be, similar to the test links already described is held by the screws 61^c and 62^c. A conductor 68 is provided connected with a terminal 51^c, this being held in place in part by a screw 54^c. A conductor 69 is provided which is connected with a terminal 52^c and is held in place by means of screws 55^c and 63^c. A movable test link 53^c is provided, this being held by means of the screws 54^c and 55^c. A test link 64^c may be provided as indicated in dot-and-dash lines for bypassing the meter, this link being held by the screws 60^c and 63^c.

From the foregoing description, it will be seen that I have provided meter testing devices which are capable of being used in the same way as those already fully described in connection with Figs. 9 to 12 and which are conveniently and accessibly mounted without the use of separate supporting means such as the blocks 50, 50. The testing means although mounted on the main rear supporting device are nevertheless so mounted as not to be obstructed by the fuse and switch parts and the arrangement is such that the movable members of the switches can be entirely

removed without disturbing any parts of the testing means. It will further be apparent that the arrangement is such that the removable guard while permitting access to the fuse parts serves to prevent access either to the switch parts or to the testing means, these latter parts being thus fully protected against unauthorized tampering or manipulation.

10 5 What I claim is:

1. In a fused switch appliance, the combination of a rear support, a plurality of supporting elements extending forward from the support, two fuse receiving contacts directly mounted upon and contacting with two of the said elements respectively at the forward portions thereof, two pairs of opposed stationary switch contacts located at least in part behind a transverse plane through the rear parts of the fuse contacts, a rectilinearly movable switching member comprising two conducting elements insulated from each other and normally engaging the said stationary switch contacts of the corresponding pairs to establish a circuit through the appliance, and means for rectilinearly moving the switching member approximately parallelly with the face of the rear support.

2. In a fused switch appliance, the combination of a rear support, a plurality of supporting elements extending forward from the support, two fuse receiving contacts directly mounted upon and contacting with two of the said elements respectively at the forward portions thereof, two stationary switch contacts located at least in part behind a transverse plane through the rear parts of the fuse contacts and mounted directly upon the last said supporting elements respectively, two other similarly located stationary switch contacts carried by the support and arranged in opposed relationship with the first said switch contacts, a rectilinearly movable switching member comprising two conducting elements insulated from each other and normally engaging the said stationary switch contacts of the corresponding pairs to establish a circuit through the appliance, and means for rectilinearly moving the switching member approximately parallelly with the face of the rear support.

3. In a fused switch appliance, the combination of a rear support, a plurality of supporting elements extending forward from the support, two fuse receiving contacts directly mounted upon and contacting with two of the said elements respectively at the forward portions thereof, an insulating tie plate connecting the forward portions of the last said elements behind the fuse contacts, two pairs of stationary switch contacts located at least in part behind the plane of the said plate, a movable switching member

comprising two conducting elements insulated from each other and normally engaging the said stationary switch contacts of the corresponding pairs to establish a circuit through the appliance, and means for rectilinearly moving the switching member approximately parallelly with the face of the rear support.

4. In a fused switch appliance, the combination of a rear support, a plurality of supporting elements extending forward from the support, an insulating tie plate connecting two of the said elements and having holes through which the forward portions of the said elements extend, two fuse receiving contacts respectively mounted upon and contacting with the said forward portions of the said elements at the front side of the said plate, two pairs of stationary switch contacts located at least in part behind the plane of the said plate, a movable switching member comprising two conducting elements insulated from each other and normally engaging the said stationary switch contacts of the corresponding pairs to establish a circuit through the appliance, and means for rectilinearly moving the switching member approximately parallelly with the plane of the said plate.

5. In a fused switch appliance, the combination of an insulating supporting device adapted to be secured to a rear supporting wall, a plurality of supporting elements extending forward from the supporting device, two fuse receiving contacts directly mounted upon and contacting with two of the said elements respectively at the forward portions thereof, two stationary switch contacts located at least in part behind a transverse plane through the rear parts of the fuse contacts and mounted directly upon the last said supporting elements respectively, two other similarly located stationary switch contacts carried by the supporting device and arranged in opposed relationship with the first said switch contacts, a rectilinearly movable switching member comprising two conducting elements insulated from each other and normally engaging the said stationary switch contacts of the corresponding pairs to establish a circuit through the appliance, and means for rectilinearly moving the switching member approximately parallelly with the front face of the supporting device.

6. In a fused switch appliance, the combination of a rear support, a plurality of supporting elements extending forward from the support, two fuse receiving contacts directly mounted upon and contacting with two of the said elements respectively at the forward portions thereof, an insulating tie plate connecting the forward portions of the last said elements behind the fuse contacts, two stationary switch contacts located at least in part behind the plane of the said

plate and mounted directly upon the last said supporting elements respectively, two other similarly located stationary switch contacts carried by the support and arranged in opposed relationship with the first said switch contacts, a rectilinearly movable switching member comprising two conducting elements insulated from each other and normally engaging the said stationary switch contacts of the corresponding pairs to establish a circuit through the appliance, and means for rectilinearly moving the switching member approximately parallelly with the face of the rear support.

7. In a fused switch appliance, the combination of a rear support, a plurality of supporting elements extending forward from the support, two fuse receiving contacts directly mounted upon and contacting with two of the said elements respectively at the forward portions thereof, an insulating tie plate connecting the forward portions of the last said elements behind the fuse contacts, two stationary switch contacts located at least in part behind the plane of the said plate and mounted directly upon the last said supporting elements respectively, two other similarly located stationary switch contacts carried by the support and arranged in opposed relationship with the first said switch contacts, a rectilinearly movable switching member comprising an insulating element and two conducting elements carried by the insulating element and normally engaging the stationary switch contacts to establish a circuit through the appliance, the insulating element of the said switching member engaging at its front with the said plate so as to be held and guided thereby, and means for rectilinearly moving the switching member approximately parallelly with the plane of the plate.

8. In a fused switch appliance, the combination of a rear insulating supporting device adapted to be secured to a rear supporting wall, a plurality of supporting elements extending forward from the supporting device, two fuse receiving contacts directly mounted upon and contacting with two of the said elements respectively at the forward portions thereof, an insulating tie plate connecting the forward portions of the last said elements behind the fuse contacts, two stationary switch contacts located at least in part behind the plane of the said plate and mounted directly upon the last said supporting elements respectively, two other similarly located stationary switch contacts carried by the support and arranged in opposed relationship with the first said switch contacts, a rectilinearly movable switching member comprising an insulating element and two conducting elements carried by the insulating element and normally engaging the stationary switch contacts to establish a circuit

through the appliance, the insulating element of the said switching member engaging at its front edge with the said plate and at its rear edge with the said insulating supporting device so as to be held and guided between them and the said switching member as a whole being entirely free for lateral adjustment so as to be controlled as concerns such adjustment solely by the stationary switch contacts, and means for rectilinearly moving the switching member.

9. In an electric switch, the combination of a rear support, a pair of opposed stationary switch contacts carried by the support at the front thereof, a rectilinearly movable switching member comprising an insulating element and a conducting element carried by the insulating element and normally engaging the said stationary switch contacts to establish a circuit through the switch, means normally engaging the insulating element of the said member to prevent forward movement thereof, provision being made for relative lateral movement between the last said means and the said member to permit the said member to be bodily removed from the support and from the stationary switch contacts in the forward direction, and means for rectilinearly moving the switching member approximately parallelly with the face of the rear support.

10. In an electric switch, the combination of a rear support, two pairs of opposed stationary switch contacts carried by the support at the front thereof, a rectilinearly movable switching member comprising an insulating element and two conducting elements carried by the insulating element and normally engaging the said switch contacts of the corresponding pairs to establish a circuit through the switch, means normally engaging the said member to prevent forward movement thereof, the said member being movable laterally to disengage the said means and thereby permit bodily removal from the support and from the stationary switch contacts in the forward direction while the fuse contacts remain in normal positions, and means for rectilinearly moving the switching member approximately parallelly with the face of the rear support.

11. In an electric switch, the combination of a rear support, a rectilinearly movable switching member located in front of the rear support and comprising an insulating element and two longitudinally spaced conducting elements carried by the insulating element and having opposed lateral contact faces, the said switching member being entirely free for limited lateral adjustment, means normally engaging the switching member to prevent forward movement thereof, and two pairs of opposed stationary switch contacts carried by the rear support and positioned to be engaged and disengaged by the respective conducting elements of the

switching member, the said switch contacts serving as the sole means for controlling the lateral adjustment of the switching member and being sufficiently resilient to permit the said member to be moved laterally so as to disengage the means which normally prevents forward movement.

12. In a fused switch appliance, the combination of a rear support, a pair of fuse receiving contacts carried by the support and accessible from the front, two pairs of opposed stationary switch contacts carried by the support at the front thereof, a rectilinearly movable switching member comprising two conducting elements insulated from each other and normally engaging the said stationary switch contacts of the corresponding pairs to establish a circuit through the appliance, the said member being bodily removable from the support and from the stationary switch contacts in the forward direction while the fuse contacts remain in normal positions, and means for rectilinearly moving the switching member approximately parallelly with the face of the rear support.

13. In a fused switch appliance, the combination of a rear support, two pairs of fuse receiving contacts arranged side by side at the center of the appliance, two switching devices carried by the support at the front thereof and each comprising two pairs of opposed stationary switch contacts and a rectilinearly movable switching member, the said members each comprising a flat insulating element and two conducting elements carried by the insulating element and normally engaging the said stationary switch contacts of the corresponding pairs to establish a circuit through the appliance and the said members being positioned at opposite sides of the two pairs of fuse contacts and being bodily removable from the support and from the stationary switch contacts in the forward direction while the fuse contacts remain in normal positions, and means for rectilinearly moving the two switching members approximately parallelly with the face of the rear support.

14. In a fused switch appliance, the combination of a rear support, a pair of fuse receiving contacts carried by the support and accessible from the front, a pair of opposed stationary switch contacts carried by the support at the front thereof, a rectilinearly movable switching member comprising an insulating element and a conducting element carried by the insulating element and normally engaging the said stationary switch contacts to establish a circuit through the appliance, means normally engaging the insulating element of the said member to guide the said member and to normally prevent forward movement thereof, the said means serving when desired to permit the said member to be bodily removed from the support

and from the stationary switch contacts in the forward direction while the fuse contacts remain in normal positions, and means for rectilinearly moving the switching member approximately parallelly with the face of the rear support.

15. In a fused switch appliance, the combination of a rear support, a pair of fuse receiving contacts carried by the support and accessible from the front, two pairs of opposed stationary switch contacts carried by the support at the front thereof, a rectilinearly movable switching member comprising an insulating element and two conducting elements carried by the insulating element and normally engaging the said stationary switch contacts of the corresponding pairs to establish a circuit through the appliance, means normally engaging the insulating element of the said member to guide the said member and to normally prevent forward movement thereof, provision being made for relative lateral movement between the last said means and the said member to permit the said member to be bodily removed from the support and from the stationary switch contacts in the forward direction while the fuse contacts remain in normal positions, and means for rectilinearly moving the switching member approximately parallelly with the face of the rear support.

16. In a fused switch appliance, the combination of a rear support, a pair of fuse receiving contacts carried by the support and accessible from the front, two pairs of opposed stationary switch contacts carried by the support at the front thereof, a rectilinearly movable switching member comprising an insulating element and two conducting elements carried by the insulating element and normally engaging the said stationary switch contacts of the corresponding pairs to establish a circuit through the appliance, means normally engaging the insulating element of the said member to normally prevent forward movement thereof, the said member being movable laterally to disengage the said means and thereby permit bodily removal from the support and from the stationary switch contacts in the forward direction while the fuse contacts remain in normal positions, and means for rectilinearly moving the switching member approximately parallelly with the face of the rear support.

17. In a fused switch appliance, the combination of a rear support, two supporting elements extending forward from the support, two fuse receiving contacts carried by the respective supporting elements and accessible from the front, an insulating member connecting the two said supporting elements near the forward ends thereof behind the fuse contacts, two pairs of opposed stationary switch contacts carried by the support at

the front thereof and behind the plane of the insulating member, a rectilinearly movable switching member comprising two conducting elements insulated from each other and normally engaging the said stationary switch contacts of the corresponding pairs to establish a circuit through the appliance, the said member being bodily removable from the support and from the stationary switch contacts in the forward direction while the fuse contacts remain in normal positions, and means for rectilinearly moving the switching member approximately parallelly with the face of the rear support.

18. In a fused switch appliance, the combination of a rear support, two supporting elements extending forward from the support, two fuse receiving contacts carried by the respective supporting elements and accessible from the front, a pair of opposed stationary switch contacts carried by the support at the front thereof, a rectilinearly movable switching member comprising an insulating element and a conducting element carried by the insulating element and normally engaging the said stationary switch contacts to establish a circuit through the appliance, an insulating member connecting the two said supporting elements near the forward ends thereof and behind the fuse contacts, the said member normally preventing forward movement of the insulating element of the movable switching member but nevertheless serving when desired to permit the said member to be bodily removed from the support and from the stationary switch contacts in the forward direction while the fuse contacts remain in normal positions, and means for rectilinearly moving the switching member approximately parallelly with the face of the rear support.

19. In a fused switch appliance, the combination of a rear support, two supporting elements extending forward from the support, two fuse receiving contacts carried by the respective supporting elements and accessible from the front, two pairs of opposed stationary switch contacts carried by the support at the front thereof, a rectilinearly movable switching member comprising an insulating element and two conducting elements carried by the insulating element and normally engaging the said stationary switch contacts of the corresponding pairs to establish a circuit through the appliance, an insulating member connecting the said supporting elements near the forward ends thereof behind the fuse contacts and at its side overlapping the said movable switching member to a slight extent so that forward movement of the switching member is normally prevented and so that disengagement of the switching member from the connecting member is permitted by lateral movement of

the former, the said switching member being then bodily removed from the support and from the stationary switch contacts in the forward direction while the fuse contacts remain in normal positions, and means for rectilinearly moving the switching member approximately parallelly with the face of the rear support.

20. In an enclosed fused switch, the combination of an enclosing cabinet having an openable front cover with an opening therein, a pair of fuse receiving contacts mounted in the cabinet in position to be accessible through the said opening in the cabinet cover when the cover is closed, a switching device in the cabinet behind a transverse vertical plane at the rear of the fuse contacts comprising a pair of opposed stationary switch contacts and a rectilinearly movable switching member including an insulating element and a conducting element carried by the insulating element and normally engaging the said stationary switch contacts to establish a circuit between them, and a guard member associated with the cabinet cover at the opening therein to prevent access through the opening to conducting parts within the cabinet other than the said fuse contacts, the said guard member being movable out of its normal position to permit access to the switching device.

21. In an enclosed fused switch, the combination of an enclosing cabinet having an openable front cover with an opening therein, a pair of fuse receiving contacts mounted in the cabinet in position to be accessible through the said opening in the cabinet cover when the cover is closed, a switching device in the cabinet behind a transverse vertical plane at the rear of the fuse contacts comprising a pair of opposed stationary switch contacts and a rectilinearly movable switching member including an insulating element and a conducting element carried by the insulating element and normally engaging the said stationary switch contacts to establish a circuit between them, the said switching member being bodily removable from the stationary switch contacts in the forward direction while the said fuse contacts remain in normal positions, means for rectilinearly moving the switching member approximately parallelly with the rear wall of the cabinet, and a guard member associated with the cabinet cover at the opening therein to prevent access through the opening to conducting parts within the cabinet other than the said fuse contacts, the said guard member being movable out of its normal position to permit removal of the switching member in the forward direction as aforesaid.

22. In an enclosed fused switch, the combination of an enclosing cabinet having an openable front cover with an opening therein, a plurality of supporting elements extending forward from the rear wall of the cabinet,

- a pair of fuse receiving contacts directly mounted upon and connecting with two of the said elements respectively at the forward portions thereof, the said contacts being in position to be accessible through the said opening in the cabinet cover when the cover is closed, a switching device in the cabinet behind a transverse vertical plane at the rear of the fuse contacts comprising a pair of opposed stationary switch contacts and a rectilinearly movable switching member including an insulating element and a conducting element carried by the insulating element and normally engaging the said stationary switch contacts to establish a circuit between them, one of the switch contacts of each pair being mounted directly on a corresponding one of the said supporting elements, means for rectilinearly moving the switching member approximately parallelly with the rear wall of the cabinet, and a guard member associated with the cabinet cover at the opening therein to prevent access through the opening to conducting parts within the cabinet other than the said fuse contacts, the said guard member being movable out of its normal position to permit access to the switching device. 23. In an enclosed fused switch, the combination of an enclosing cabinet having an openable front cover with an opening therein, a plurality of supporting elements extending forward from the rear wall of the cabinet, a pair of fuse receiving contacts directly mounted upon and contacting with two of the said elements respectively at the forward portions thereof, the said contacts being in position to be accessible through the said opening in the cabinet cover, a relatively small insulating plate parallel with the rear wall of the cabinet and connecting the forward portions of the said supporting elements behind the fuse contacts, a switching device in the cabinet behind the plane of the said plate comprising a pair of opposed stationary switch contacts and a rectilinearly movable switching member including an insulating element and a conducting element carried by the insulating element and normally engaging the said stationary switch contacts to establish a circuit between them, the contacting parts of the said switching device being located out of direct register with the said insulating plate so as to be clearly visible and easily accessible with the plate in place, means for rectilinearly moving the switching member approximately parallelly with the rear wall of the cabinet, and a guard member associated with the said plate and with the cabinet cover at the opening therein to prevent access through the opening to conducting parts within the cabinet other than the said fuse contacts, the said guard member being movable out of its normal position to permit free access to the switching parts. 24. In an enclosed fused switch, the combination of an enclosing cabinet having an openable front cover with an opening therein, a plurality of supporting elements extending forward from the rear wall of the cabinet, a pair of fuse receiving contacts directly mounted upon and contacting with two of the said elements respectively at the forward portions thereof, the said contacts being in position to be accessible through the said opening in the cabinet cover when the cover is closed, an insulating plate parallel with the rear wall of the cabinet and connecting the forward portions of the said supporting elements behind the fuse contacts, a switching device in the cabinet behind the plane of the said plate comprising a pair of opposed stationary switch contacts and a rectilinearly movable switching member including an insulating element and a contacting element carried by the insulating element and normally engaging the said stationary switch contacts to establish a circuit between them, the said switching member being bodily removable from the stationary switch contacts in the forward direction while the said fuse contacts and the said connecting plate remain approximately in their normal positions, means for rectilinearly moving the switching member approximately parallelly with the rear wall of the cabinet, and a guard member associated with the said plate and with the cabinet cover at the opening therein to prevent access through the opening to conducting parts within the cabinet other than the said fuse contacts, the said guard member being movable out of its normal position to permit removal of the switching member in the forward direction as aforesaid. 25. In an enclosed fused switch, the combination of an enclosing cabinet having an operable front cover with an opening therein, a plurality of supporting elements extending forward from the rear wall of the cabinet, a pair of fuse receiving contacts directly mounted upon and contacting with two of the said elements respectively at the forward portions thereof, the said contacts being in position to be accessible through the said opening in the cabinet cover, an insulating plate parallel with the rear wall of the cabinet and connecting the forward portions of the said supporting elements behind the fuse contacts, a switching device in the cabinet behind the plane of the said plate comprising two pairs of opposed stationary switch contacts and a rectilinearly movable switching member including an insulating element and two conducting elements carried by the insulating element and normally engaging the said stationary switch contacts of the corresponding pairs to establish a circuit between them, the said switching member normally engaging it at the front with the said connecting plate and being movable laterally to disengage the plate and permit bodily re-

- removal from the stationary switch contacts in the forward direction while the said fuse contacts and the said plate remain approximately in their normal positions, means for rectilinearly moving the switching member approximately parallelly with the rear wall of the cabinet, and a guard member associated with the said plate and with the cabinet cover at the opening therein to prevent access through the opening to conducting parts within the cabinet other than the said fuse contacts, the said guard member being movable out of its normal position to permit removal of the switching member in the forward direction as aforesaid.
26. In an enclosed fused switch, the combination of an enclosing cabinet having an openable front cover with an opening therein, four supporting elements extending forward from the rear wall of the cabinet, two pairs of fuse receiving contacts directly mounted upon and contacting with the said elements respectively at the forward portions thereof, the said pairs of contacts being arranged side by side in position to be accessible through the said opening in the cabinet cover, a transverse insulating plate connecting the forward portions of all of the said supporting elements behind the fuse contacts, two switching devices in the cabinet behind the plane of the said plate and each comprising a pair of opposed stationary switch contacts and a rectilinearly movable switching member including an insulating element and a conducting element carried by the insulating element and normally engaging the said stationary switch contacts to establish a circuit between them, means for rectilinearly moving the switching members approximately parallelly with the rear wall of the cabinet, and a removable guard member of insulating material in the cabinet normally surrounding the fuse contacts and cooperating with the plate to prevent access through the cover opening to conducting parts within the cabinet other than the said fuse contacts, the said guard member including a partition normally located between the said pairs of contacts.
27. In an enclosed fused switch, the combination of an enclosing cabinet having an openable front cover with an opening therein, a pair of fuse receiving contacts mounted in the cabinet in position to be accessible through the said opening in the cabinet cover when the cover is closed, a switching device in the cabinet behind a transverse vertical plane at the rear of the fuse contacts comprising a pair of opposed stationary switch contacts and a rectilinearly movable switching member including an insulating element and a conducting element carried by the insulating element and normally engaging the said stationary switch contacts to establish a circuit between them, means for rectilinearly moving the switching member approximately parallelly with the rear wall of the cabinet, and a guard member normally preventing access through the cover opening to conducting parts within the cabinet other than the said fuse contacts, the said guard member being movable out of its normal position to permit access to the switching device and being held by the cover when closed so that it is not so moveable.
28. In an enclosed fused switch, the combination of an enclosing cabinet having an openable front cover with an opening therein, a pair of fuse receiving contacts mounted in the cabinet in position to be accessible through the said opening in the cabinet cover when the cover is closed, a switching device in the cabinet behind a transverse vertical plane at the rear of the fuse contacts comprising a pair of opposed stationary switch contacts and a rectilinearly movable switching member including an insulating element and a conducting element carried by the insulating element and normally engaging the said stationary switch contacts to establish a circuit between them, means for rectilinearly moving the switching member approximately parallelly with the rear wall of the cabinet, and a guard member normally preventing access through the cover opening to conducting parts within the cabinet other than the said fuse contacts, the said guard member being movable out of its normal position to permit access to the switching device and being held by the cover when closed so that it is not so moveable.
29. In an enclosed fused switch, the combination of an enclosing cabinet having an openable front cover with an opening therein, a pair of fuse receiving contacts mounted in the cabinet in position to be accessible through the said opening in the cabinet cover when the cover is closed, a switching device in the cabinet behind a transverse vertical plane at the rear of the fuse contacts comprising a pair of opposed stationary switch contacts and a rectilinearly movable switching member including an insulating element and a conducting element carried by the insulating element and normally engaging the said stationary switch contacts to establish a circuit between them, the said switching member being

- ing bodily removable from the stationary switch contacts in the forward direction while the said fuse contacts remain in normal positions, means for rectilinearly moving the switching member approximately parallelly with the rear wall of the cabinet, and a guard member normally preventing access through the cover opening to conducting parts within the cabinet other than the said fuse contacts, the said guard member being movable out of its normal position to permit removal of the switching member in the forward direction as aforesaid and being held by the cover when closed so that it is not so movable.
30. In an enclosing fused switch, the combination of an enclosing cabinet having an openable front cover with an opening therein, a pair of fuse receiving contacts mounted in the cabinet in position to be accessible through the said opening in the cabinet cover when the cover is closed, a switching device in the cabinet behind a transverse vertical plane at the rear of the fuse contacts comprising a pair of opposed stationary switch contacts and a rectilinearly movable switching member including an insulating element and a conducting element carried by the insulating element and normally engaging the said stationary switch contacts to establish a circuit between them, means for rectilinearly moving the switching member approximately parallelly with the rear wall of the cabinet, a guard member associated with the cabinet cover at the opening therein to prevent access through the opening to conducting parts within the cabinet other than the said fuse contacts, and means independent of the cover for normally holding the guard in place but adapted to permit its removal and thus permit access to the switching device.
31. In an enclosed fused switch, the combination of an enclosing cabinet having an openable front cover with an opening therein, a plurality of supporting elements extending forward from the rear wall of the cabinet, a pair of fuse receiving contacts directly mounted upon and contacting with two of the said elements respectively at the forward portions thereof, the said contacts being in position to be accessible through the said opening in the cabinet cover when the cover is closed, a switching device in the cabinet behind a transverse vertical plane at the rear of the fuse contacts comprising a pair of opposed stationary switch contacts and a rectilinearly movable switching member including an insulating element and a conducting element carried by the insulating element and normally engaging the said stationary switch contacts to establish a circuit between them, means for rectilinearly moving the switching member approximately parallelly with the rear wall of the cabinet, a guard member associated with the cabinet cover at the opening therein to prevent access through the
- opening to conducting parts within the cabinet other than the said fuse contacts, and means for removably connecting the guard directly with the said supporting elements independently of the fuse contacts.
